WITNESS:

Robert P. Mitchell

UNITED STATES PATENT OFFICE.

OSCAR NEBEL, OF HATBORO, PENNSYLVANIA, ASSIGNOR TO PHILADELPHIA METAL DRYING FORM COMPANY, OF PHILADELPHIA, PENNSYLVANIA, A CORPORATION OF DELAWARE.

HOSIERY-DRYING FORM.

Application filed May 28, 1926. Serial No. 112,194.

My invention relates to hosiery drying forms.

Heretofore in the drying of hosiery, after it has been dyed and the excess moisture removed in a whizzer, the hosiery is placed on metal forms heated by the introduction of steam into their interiors, or by electricity.

The hollow, metal drying form has proved highly efficient in the drying of hosiery and also serves the further purpose of giving to the hosiery a pressed and finished appearance enabling it to be packed, without further treatment, after removal from the forms.

The hollow metal forms, heretofore used, have been constructed for a single size of hosiery, or of a size enabling a given form to accommodate a size and half size. Thus, for the accommodation of hosiery of the customary various sizes, there is required an unnecessarily large number of forms.

Efforts have been made to meet the problem of handling hosiery of different sizes by providing forms having detachable toe pieces, the form being adapted to various sizes by the application of different toe pieces. Such forms have proved advantageous, but the detachable toe is not an entirely satisfactory solution of the problem.

Now, it is the object of my invention to provide a hosiery drying form so constructed as to be readily adjustable for the reception of hosiery of any size.

Having now indicated, in a general way, the nature and purpose of my invention, I will proceed to a detailed description thereof with reference to the accompanying drawings in which there is illustrated a preferred embodiment and in which:

Fig. 1, is a rear view of a hosiery drying form, embodying my invention.

Fig. 2, is a fragmentary view, partly in section, of the subject of Figure 1, showing a detail of construction.

Fig. 3, is a sectional view on line 3—3 Figure 2.

Fig. 4, is a perspective view of a detachable heel.

In the drawings *a* indicates a hollow metal form provided with a base *b*, adaptable for connection to a support for the form. The

back and front walls of the form are flat and in substantial parallelism, being separated, and the interior of the form divided by a partition *c*. The edge portions of the walls are brought together to form bevelled edges *d*.

The upper end portion *e* of the form is shaped to receive the foot portion of a stocking, the heel portion being received on a separable heel portion *f* shaped in the form of the usual French heel.

The rear face of the heel portion *f* is made flat so as to bear against the rear face of the form and is provided with a groove *g*.

The rear face of the form is provided with a projecting guide *h*, which extends longitudinally of the form and is provided with a series of threaded holes *i* and a series of transverse lines *j* in association with which is a numeral indicating a hosiery size or half size.

The heel member *f* is adapted to be placed with its rear face bearing against the form in such a position that the guide *h* will be within the groove *g*. Thus the heel member will be slideable with relation to the foot portion *e* of the form and its lower edge may be aligned with any one of the lines *j*. The lines *j* are so located with relation to the foot portion of the form as to indicate the proper position of the heel for any one of several different sizes or half sizes of hosiery.

The heel member *f* is adapted to be secured to the form in any adjusted position by means of a screw *k*, which passes through an aperture *l* in the heel member and may be entered in any one of the holes *i* in the member *h*.

It will be understood that the holes *i* are so located with relation to the lines *j* and the aperture *l* is so located with relation to the lower edge of member *f* that when the lower edge of member *f* is aligned with one of the lines *j*, the aperture *l* will be aligned with one of the holes *i*.

It will now be observed that by virtue of my invention, a form is provided of such a structure as to be readily adapted to hosiery of various sizes by merely adjusting the position of the heel, which it will be noted need not be removed from the form for adjustment.

Having now fully described my invention, what I claim and desire to protect by Letters Patent is:—

1. A hosiery drying form having opposite substantially parallel faces, a foot receiving portion formed at one end of said form, a longitudinally extending guide positioned on and extending outwardly from one of said faces adjacent the foot receiving portion, a separate heel receiving and folding member grooved for slidable engagement with said guide and means for securing said member in different positions longitudinally of said guide to cooperate with the foot receiving portion to receive the feet and heels of hosiery of different sizes.
2. A hosiery drying form comprising side members spaced in substantial parallelism and formed to provide foot and leg receiv-

ing portions, a guide positioned on and extending longitudinally and outwardly of one of the side members, a separate heel receiving and folding member grooved to slidably engage said guide, a plurality of spaced openings in said guide arranged longitudinally thereof, and means carried by said heel member at one point thereof adapted to extend into any one of said openings to secure said member to said heel guide in different positions longitudinally of the guide to cooperate with the foot receiving portion to receive the feet and heels of hosiery of different sizes.

In testimony of which invention, I have hereunto set my hand, at Hatboro, Pa., on this 20th day of May, 1926.

OSCAR NEBEL.
